UNITED STATES PATENT OFFICE.

JAMES W. MALOY, OF MARIETTA, GEORGIA.

LUBRICATING DEVICE FOR RAILWAY-CARS.

SPECIFICATION forming part of Letters Patent No. 402,952, dated May 7, 1889.

Application filed July 18, 1888. Serial No. 280,293. (No. 1)

To all whom it may concern:

Be it known that I, JAMES W. MALOY, a citizen of the United States, residing in Marietta, county of Cobb, and State of Georgia, have invented certain new and useful Improvements in Railway-Cars, of which the following is a specification.

My invention relates to railway-cars; and my invention consists in the combination, with the car-axle boxes, of a pump and connections, as fully set forth hereinafter, whereby to positively maintain a circulation of the lubricating material through the several boxes and a continuous supply of the lubricating material to the said boxes.

In the accompanying drawings, Figure 1 is a sectional elevation of a railway-car truck and part of the platform of the car, illustrating my invention in connection therewith. Fig. 2 is a transverse section of one of the boxes, and Fig. 3 is a transverse vertical section of the pump illustrated in Fig. 1. Fig. 4 is a longitudinal section of the axle-box.

A represents one of the boxes and A' another of the boxes of a four-wheeled truck, which boxes contain bearings 22 for the journals of the axles 3, to which the wheels 4 are attached, and the said boxes slide in guides upon the truck-frame B, which rests upon springs 5, of any suitable character, having their bearings upon the boxes, and the platform C of the car has its bearing, as usual, upon the center beam, 6, of the truck.

Upon the truck is mounted a pump, D, of any suitable character, the same, as shown, being a cylinder-pump with a cylinder, 7, piston 8, piston-rod 9, an inlet-pipe, 10, at the upper end, and discharge-pipe 11, communicating with the lower end, and this pump is operated in any suitable manner, preferably by the rotation of the wheels of the truck—as, for instance, through an eccentric, 12, upon one of the axles operating upon the lever 13, pivoted to the truck-frame extending over the eccentric and drawn downward by a spring, 14.

The piston 8 is perforated, and provided with a valve, 15, which opens on the ascent of the piston, so that when the latter moves down the piston will tend to expel the contents of the cylinder from the lower end and to draw

in a supply at the upper end, which supply passes below the piston upon the opening of the valve when the piston ascends.

The pipes 10 and 11 communicate with two main conducting-pipes, 17 and 18, carried by the car, the connections being formed by flexible continuations with the said pipes 10 and 11, which permit the swinging of the truck without straining of the pipes.

Each axle-box of the truck and of the car, 60 whatever may be the number of axles and trucks, is provided with an outlet port or pipe, 19, at the lower end, and with an inlet port or pipe, 20, at the upper end, and the ports 20 communicate through flexible pipes 21 with the main pipe 18, and the ports 19 through flexible pipes 22 with the main pipe 17.

As the piston descends, the oil or lubricant at the bottom of each box is exhausted through the pipe 22 and pipe 17 into the upper end of the pump, and as the piston ascends the oil passes through the lower end of the pump, and on the next descent of the piston the oil is forced through the pipe 11 and pipe 18 into all of the pipes 21 and into the top of each box, and is thrown onto the journal or bearing in such manner as to absolutely insure the effective lubrication of the journal. By thus maintaining an enforced circulation of the oil from each box to a main or central pump, and from the latter back to the several boxes, I effectually prevent the boxes from becoming heated. Thus each journal is supplied with oil by the positive and forcible injection of a stream of oil upon the journal or 85 its bearing. Should the oil in any one of the boxes become gummy from any cause, it is speedily withdrawn and diluted by the larger body of oil in the pump-cylinder, and the lubricating quality of the oil in each box is 90 maintained at as high a standard as that of the oil in the other boxes. No one of the boxes can be deprived of its oil by leakage so long as there is any oil in the other boxes.

It will be evident that the conducting-pipes 95 may be differently arranged and connected with the boxes and pump in different ways without departing from the main features of my invention, and that there may be an independent connection between each box and the 100

pump, in which case the pipes 21 and 22 would extend directly from each box to the cylinder of the pump, as shown in dotted lines, Fig. 1.

Without limiting myself to the precise construction and arrangement of parts shown, I claim—

1. The combination, with the axle-boxes of a railway-car, of a single pump communicating with each box of the car at its upper and lower parts to maintain a circulation of oil through the pump and through each box, the pump being connected with one of the axles to be operated positively by the rotation thereof, substantially as set forth.

2. The combination, in a railway-car, of a pump communicating with pipes 17 and 18, carried by the car, and a communication between the pipe 17 and the lower end of each axle-box of the car and between the pipe 18

and the upper end of each axle-box of the car, substantially as set forth.

3. The combination of a car-body, one or more swinging trucks supporting the same, and pipes 17 and 18, carried by the body, a pump communicating through flexible pipes with the pipes 17 and 18, and a flexible pipe connecting the lower portion of each car-axle box and the pipe 17, and another flexible pipe connecting the upper portion of each car-axle box and the pipe 18, substantially as set forth.

In testimony whereof I have signed my name to this specification in the presence of two subscribing witnesses.

JAMES W. MALOY.
